M. HAEBERLEIN:
OIL BRAKE FOR SPEED GOVERNORS.
APPLICATION FILED JUNE 2, 1919.

1,318,749.

Patented Oct. 14, 1919.

C. P. Goepel

UNITED STATES PATENT OFFICE.

MAX HAEBERLEIN, OF BROOKLYN, NEW YORK.

OIL-BRAKE FOR SPEED-GOVERNORS.

1,318,749.

Specification of Letters Patent. Patented Oct. 14, 1919.

Application filed June 2, 1919. Serial No. 301,252.

To all whom it may concern:

Be it known that I, MAX HAEBERLEIN, a citizen of the United States, and a resident of the borough of Brooklyn, county of 5 Kings, city and State of New York, have invented certain new and useful Improvements in Oil-Brakes for Speed-Governors, of which the following is a specification.

This invention relates to certain improvements 10 in oil brakes for speed governors of that general class shown and described in Letters Patent No. 821,359, May 22nd, 1906, and 860,913, July 23rd, 1907.

Broadly considered, the improvements 15 embodied in the present application are designed with a view to obtaining a better means for controlling and regulating the passage of oil from the cylinder chamber to the piston chamber of the brake illustrated and described in my prior patent, 20 last above referred to.

The construction and arrangement disclosed in Patent No. 860,913, has been found to be somewhat disadvantageous in practice in that the area of the openings or passages which afford communication between the two oil chambers when the piston moves from its median position, gradually increases in proportion to the length of the 25 piston rod stroke as the piston rod moves in one direction away from its median position and decreases to a corresponding extent when the piston rod moves in a relatively opposite direction. Thus it will be at once 30 manifest that as the area of the oil passage is constantly changing during the stroke of the piston rod, the piston is caused to return to its median position with variable 35 velocity. The extent of such variation in 40 velocity is influenced by two causes, namely, first, by the variation in area of the passage affording communication between the two oil chambers during a stroke of the piston, and secondly by the variable tension of the 45 springs which serve to return the piston to a median position. This variation in velocity of the piston travel, from the standpoint of good speed regulation, is undesirable, and the present invention is therefore 50 devised with a view to practically eliminating the first and principal cause thereof.

It is accordingly the primary object and purpose of the present improvement to overcome the above noted objection to which 55 my prior patented inventions are open, and

to provide a construction wherein the area of the oil passages or openings through which the oil passes from one chamber to the other, will remain the same during the full stroke of the piston rod so that the 60 piston will be returned to its median position with considerably less variation in velocity, such velocity depending solely on the tension of the springs which are provided for the purpose of yieldingly resisting relative movement of the rod and the piston, and tend to return the piston to its median position. I have succeeded in attaining this 65 desirable result by means of a very simple improvement in the patented constructions, 70 such improvement however, also making it possible to increase or decrease the area of the passages or openings and thereby regulate the volume of oil flowing therethrough 75 as the particular operating conditions may necessitate so as to return the piston to its median position with the desired velocity.

Having the aforementioned objects in view, the present invention comprehends certain novel and improved combinations of 80 mechanical elements, and the structural characteristics thereof, as will be more fully developed in the following description and subsequently incorporated in the subjoined 85 claims.

In the accompanying drawings, wherein I have illustrated one practical embodiment 90 of my invention, and in which like reference characters designate corresponding parts throughout the several views,

Figure 1 is a vertical sectional view through the oil brake showing the piston in its normal median position;

Fig. 2 is a horizontal section taken on the line 2—2 of Fig. 1;

Fig. 3 is a section taken on the line 3—3 of Fig. 1, showing the oil passages positioned to receive the maximum quantity of oil; and

Fig. 4 is a similar view showing the valve 100 member adjusted to decrease the inlet area of the oil passages.

Referring in detail to the drawing, 5 designates the brake cylinder in which the piston 6 is engaged for reciprocatory movement. The inner wall of the cylinder 5 is formed with a keyway 7 to receive a suitable key lug 8 on the periphery of the piston 6 whereby rotation of the piston within the cylinder is prevented. The piston 6 is 110

formed with a relatively thick end wall 9, the other end of the piston which is hollow, being closed by a removable head 10.

The piston rod 11 is of tubular construction and is loosely fitted through an opening 12 centrally formed in the end wall 9 of the piston. At each side of the piston wall 9, a pressure spring 13 is arranged, said springs at one of their ends respectively bearing against the opposite faces of the bottom wall of the piston, while their other ends are engaged upon suitable seats formed on the nuts 14 which are threaded upon the tubular piston rod 11. These springs are sufficiently stiff to impart the requisite stability to the governor and by the adjustment of the nuts 14, the tension of said springs can be regulated as desired. The nuts 14 are securely locked in their adjusted positions by means of the jam nuts 15 also threaded on the piston rod 11.

The upper end of the piston rod 11 is formed with a yoke 16 having an apertured ear 17 adapted for connection by any suitable means to the movable lever of the governor mechanism (not shown), while a similar ear 18 is formed upon the lower end wall of the brake cylinder 5 for pivotal connection to the standard or other fixed part, as shown for instance, in my prior Patent No. 821359, above referred to.

The tubular piston rod 11 is provided in its outer surface and at diametrically opposite points with the longitudinally extending grooves or channels 19. Transverse openings 20 centrally communicate with these channels and upon the inner face of the piston rod. These grooves or channels 19 are of such length and so shaped that when the piston 6 is in its normal median position, they terminate at their opposite ends within the openings 12 in the bottom wall of the piston. Thus, it will be impossible for oil to pass from the chamber of the cylinder 5 into the chamber of the piston 6 or vice versa.

Within the tubular piston rod 11, a cylindrical valve member 21 is fitted, and is rotatable with respect to the piston rod. The lower end of the valve member is formed with a laterally projecting flange 22 engaging the end of the piston rod while a head 23 is provided upon the upper end of the valve member and is disposed within the yoke 16. Thus, the valve member and piston rod will be held against relative axial movement. The head 23 is formed with a knurled flange 24 by means of which the valve member can be conveniently rotated.

60 The valve member 21 at a point intermediate of its ends is formed with a passage 25. The lower end of this passage is transversely extended through the valve member and opens upon the periphery thereof as indicated at 26, such open end of the passage

being in horizontal alignment with one of the openings 20 of the wall of the tubular piston rod. At its upper end, the passage 25 is also transversely extended as at 27 and communicates with an annular groove 28 formed in the periphery of the valve member. The wall of the piston rod 11 is provided with an opening 29 which affords communication between this groove and the chamber of the piston 6.

75 The valve member 21 is also provided with a second longitudinal passage 29 one end of which opens upon the lower end face of the valve member and is in communication with the chamber of the cylinder 5. At its upper 80 end the passage 29 is transversely extended as at 30 and is adapted to register with the other of the transverse openings 20 in the wall of the piston rod 11.

Assuming that in the operation of the governor, the piston rod 11 is moved downwardly so as to position the lower ends of the grooves or channels 19 below the bottom face of the wall 9, in which movement it will, of course, be apparent that the piston 6 will also move from its median position and the oil contained within the cylinder be placed under greater pressure than the body of oil within the piston, the oil from the cylinder chamber will enter one of the 95 grooves 9 and flow upwardly through the passage 25 in the valve member and outwardly from the upper end of said passage through the passage 29 into the piston chamber. Thus, the pressures in the two 100 chambers will be equalized and the piston returned to its median position. If the valve member is in the position seen in Fig. 3, and the lower end of the passage 25 is in full registration with the opening 20, the oil will 105 flow very rapidly and in maximum volume from the cylinder chamber into the piston chamber, and the piston will be rapidly returned to its median position. It is, however, to be noted that the area of this passage will remain constant during the entire 110 stroke of the piston rod and consequently the velocity at which the piston is returned to its median position is governed or determined only by the action of the springs. 115 This velocity of the return movement of the piston may be controlled and regulated by simply adjusting the valve member 21 within the tubular piston pipe. Thus, if the valve member is rotated to dispose the 120 passages therein with relation to the openings 20 in the wall of the valve rod as seen in Fig. 4, the passage of the oil from one chamber to the other is throttled and the movement of the piston as it returns to its 125 median position will be relatively slow. Of course it will be understood that when the piston rod is moved upwardly, the reverse of the above described operation takes place and the oil will then pass downwardly from 130

the piston chamber through the passage 29 in the valve member into the chamber of the cylinder 5.

It will be readily appreciated from the foregoing that by means of the present improvements, I have succeeded in entirely obviating the practical disadvantage inherent in my prior patented constructions heretofore referred to. At the same time, however, the construction of the oil brake remains comparatively simple so that it will be positive and reliable in its operation and will not easily get out of order or require frequent repair. It is to be understood that the brake may be constructed in many different sizes and that, if desired, the upper pressure spring 13 may be dispensed with so that the piston would then move downwardly by gravity of its own weight.

In the preceding description and the accompanying drawing I have disclosed one practical embodiment of the invention, which, however, may likewise be exemplified in numerous alternative construction. Accordingly the invention as herein claimed is to be considered as inclusive of all legitimate equivalents for the various elements employed, as well as other contemplated arrangements thereof, which may satisfactorily accomplish the desired results.

I claim:

1. An oil brake for motor speed governors, comprising a brake cylinder, a piston in said cylinder having a chamber out of communication with the cylinder chamber in the normal operation of the governor, a piston rod connected with the speed governor and axially movable relative to the piston, means normally tending to maintain the piston in a median position within the cylinder, and means for maintaining an oil passage of constant area between said chambers in the relative movement of the piston and the piston rod.
2. An oil brake for motor speed governors, comprising a brake cylinder, a piston in said cylinder having a chamber, a piston rod connected with the speed governor and axially movable relative to the piston, means normally tending to maintain the piston in a median position within the cylinder, a valve member associated with the piston rod and adjustable relative thereto, said valve member and piston rod having co-operating means affording a passage of constant area during the piston rod stroke through which the oil flows from the cylinder chamber into the piston chamber or vice versa during the stroke of the piston rod in one direction.
3. An oil brake for motor speed governors, comprising a brake cylinder, a hollow piston to reciprocate within said cylinder, a piston rod adapted to be connected with the governor and axially movable relative to the

piston, means normally tending to maintain the piston in a median position, a valve member associated with the piston rod and adjustable relative thereto, said valve member and the piston rod having co-operating means permitting of the passage of oil in predetermined quantity from one oil chamber into the other during the stroke of the piston in one direction.

4. An oil brake for motor speed governors, comprising a brake cylinder, a hollow piston to reciprocate within said cylinder, a tubular piston rod extending through the piston and axially movable relative thereto, a valve member rotatably engaged within the piston rod for adjustment relative thereto, said valve member and the piston rod having co-operating passages formed therein permitting of the flow of oil in predetermined quantity from one oil chamber into the other during the stroke of the piston rod in one direction.

5. An oil brake of the class including a brake cylinder having a chambered piston therein, a piston rod and means for returning the piston to a median position within the cylinder, characterized by the provision of a passage of constant area closed by the piston when in its normal position, but affording communication between the cylinder chamber and the piston chamber in the movement of the piston to thereby permit of the passage of oil between said chambers and cause a return movement of the piston to its normal position at a velocity determined by the action of the returning means.

6. An oil brake of the class including a cylinder having a chambered piston therein, a piston rod axially movable relative to the piston, and means for returning the piston to a median position within the cylinder, characterized by the provision of means operable independently of the piston rod for regulating the flow of oil from the cylinder chamber into the piston chamber or vice versa, during the stroke of the piston in one direction to cause a return movement of the piston to its normal median position at a velocity determined by the action of said returning means.

7. An oil brake of the class including a brake cylinder having a chambered piston therein, a piston rod axially movable relative to the piston and means for returning the piston to a median position within the cylinder, characterized by the provision of means in the piston rod and operable independently thereof for variably regulating the flow of oil from the cylinder chamber into the piston chamber or vice versa during the stroke of the piston in one direction, to cause a return movement of the piston to its normal median position at a velocity determined by the action of said returning means.

8. An oil brake of the class including a
brake cylinder, having a chambered piston
therein, a piston rod axially movable relative
to the piston and means for returning
5 the piston to its normal median position
within the cylinder, characterized by the
provision of regulable orifices in the piston
rod communicating at one of their ends
10 with the cylinder and the piston chamber
respectively, and normally closed at their
other ends by the piston, said orifices afford-

ing communication between the chambers in
the relative movement of the piston and
piston rod whereby the oil pressures in said
chambers are equalized and the piston re- 15
turned to its normal median position at a
velocity determined by the action of the
returning means.

In testimony that I claim the foregoing
as my invention, I have signed my name 20
hereunder.

MAX HAEBERLEIN.
